UNITED STATES PATENT OFFICE.

WILLIAM ENGELKE, OF FORT DODGE, IOWA.

PYROTECHNIC DEVICE.

Application filed October 27, 1924. Serial No. 746,115.

To all whom it may concern:

Be it known that I, WILLIAM ENGELKE, a citizen of the United States, residing in Fort Dodge, in the county of Webster and State 5 of Iowa, have invented a certain new and useful Pyrotechnic Device, of which the following is a specification.

The object of my invention is to provide a pyrotechnic device wherein the various 10 parts can be collapsed and placed in a minimum package for shipping and storage purposes, the parts being of simple, durable and comparatively inexpensive construction.

Still a further object is to provide a number 15 of bars connected together by links wherein the parts may be spaced apart or moved close together, as desired, for supporting pyrotechnic candles or lights for display purposes.

With these and other objects in view, my 20 invention consists in the construction, arrangement and combination of the various parts of my device, whereby the objects contemplated are attained, as hereinafter more 25 fully set forth, pointed out in my claims, and illustrated in the accompanying drawings, in which:

Figure 1 is a plan view of my pyrotechnic 30 device arranged so that the words "One law" are exhibited or displayed through the use of my device.

Figure 2 is a view of the device shown in Figure 1 with the parts collapsed.

Figure 3 is a back view of a portion of 35 the device shown in Figure 2, showing the link connections.

Figure 4 is a back view of a slightly modified form of device wherein single links are connected to the supporting bars; and

Figure 5 is a detail, sectional view taken 40 on line 5—5 of Figure 1.

In the accompanying drawings, I have used the reference numeral 10 to indicate supporting bars which are connected together by toggle links 11. The links 11 are arranged near the top and bottom of the bars 10 and can be folded up so that the bars 45 rest side by side or may be spaced apart, all as clearly shown in Figure 3 of the drawings.

The bars can be connected together by links of various sizes so that in case it is desired to form any particular letter or word, the space between such letter or word 55 can be had.

In Figure 1 of the drawings, I have shown

the words "One law" and the "O" is separated from the "N" by a toggle link, which is longer than the links connecting any two of the other bars 10 together, which form 60 parts of the letters "O" or "N".

The word "One" is separated from the word "Law" by links of considerable length.

Placed upon the bars 10 may be suitable 65 pyrotechnic candles 12 held in position by nails 13 or the candles 12 may be glued to the rail or bars 10.

The bars 10, when spaced apart as shown in Figure 1, have the words "One law" 70 thereon and as the candles 12 are illuminated the letters of the words "One law" will be clearly visible.

The candles 12 are all connected together by fuses 14 and a lighting fuse 15 is also provided.

The lighting of the fuse 15 will cause all 75 of the pyrotechnic candles 12 to function.

In the arrangement of the letters "A" and "W" forming a part of the word "Law", I arrange the links 11 in different position 80 on the bars 10 so as to permit some of the bars 10 to be inclined from vertical, as clearly shown in Figure 1 to get the proper effect for the particular letter.

The toggle links may be collapsed, which 85 will cause all of the bars 10 to be brought side by side wherein the pyrotechnic device may be packed in a minimum amount of space.

Large bars can be used for forming large 90 signs.

In Figure 4 of the drawings, I have shown the bars 10 as being directly connected by single links 16 arranged near the top and bottom thereof, which will cause the 95 bars 10, when collapsed to be staggered somewhat relative to each other and yet when the links are in outspread position, all of the bars 10 will be in substantial alignment.

When a single link 16 is used, then of course, it requires a little more space to pack the entire pyrotechnic device in than when a double or toggle link 11 connection is used.

The advantage of my structure resides in the fact that I am able to form any letter with the use of the bars and links, and yet permit such letter to be folded or collapsed, as shown in Figure 2 of the drawings, where it will occupy a minimum amount of space 110 for packing and shipping.

Some changes may be made in the construction and arrangement of the various parts of my invention, without departing from the real spirit and purpose of my invention, and it is my intention to cover by my claims, any modified forms of structure or use of mechanical equivalents which may be reasonably included within their scope.

I claim as my invention:

- 10 1. A pyrotechnic device for the formation of words comprising a plurality of similar bars, links for connecting said bars together, said links being capable of pivotal movement for permitting the bars to be spaced apart or positioned side by side as and for the purposes stated.
- 15 2. A pyrotechnic device for the formation of words comprising a plurality of similar bars, toggle links for connecting said bars together, said links being capable of pivotal movement for permitting the bars to be spaced apart or positioned side by side as and for the purposes stated.
- 20 3. A pyrotechnic device for the formation of words comprising a plurality of bars, movable relative to each other for assuming either a position spaced from each other or a position adjacent to each other, and means

for retaining the bars in connected relationship and pyrotechnic candles on said bars. 30

4. A pyrotechnic device for the formation of words comprising a plurality of bars, movable relative to each other for assuming either a position spaced from each other or a position adjacent to each other, and means 35 for connecting the bars together and for permitting movement of the bars so that they assume either of their positions.

5. A pyrotechnic device for the formation of words comprising a plurality of bars, 40 movable relative to each other for assuming either a position spaced from each other or a position adjacent to each other and toggle links for securing two adjacent bars together for permitting said bars to assume 45 either of their two positions.

6. A pyrotechnic device for the formation of words comprising a plurality of bars movable relative to each other for assuming either a position spaced from each other or a position adjacent to each other and a link 50 having its ends pivotally connected to two adjacent bars for permitting said bars to assume either of their two positions.

WILLIAM ENGELKE.
